UNITED STATES PATENT OFFICE.

ADOLPH W. MALONE, OF FILLMORE, UTAH, ASSIGNOR OF ONE-THIRD TO ALBERT H. VESTAL, OF ANDERSON, INDIANA, AND ONE-THIRD TO ALVIN M. LOCKWOOD, OF SAN ANTONIO, TEXAS.

CROSS-ARM CLAMP.

Application filed February 14, 1928, Serial No. 254,308.

My invention relates to a clamp for securing a cross arm to a pole or post and it is an object of the invention to provide a clamp designed primarily for securing a cross arm of any appropriate material to a metal post such, for example, as illustrated in my Reissue Patent No. 16,684, granted July 19, 1927, but which may be used also with poles of wood, concrete or other appropriate construction without requiring the cutting of the pole or the boring of holes in the same and which renders cross arm braces unnecessary, all as will be hereinafter more particularly described and claimed.

Wooden telephone poles are ordinarily treated with a solution to exclude bacteria which promote decay. During the process of applying a cross arm to the pole a slot is cut in the pole for the reception of the cross arm and a hole is bored through the center of the pole and cross arm in which is placed a bolt which is used to fasten the parts together. It is also customary to use cross arm braces. This method of attaching the cross arm to the pole results not only in impairing the strength of the pole and cross arm due to the unusual abusive stresses of the enormous concentrated load at the point of attachment of the arm to the pole but the cutting and boring operations puncture the treated surface of the pole and allow the entrance of moisture and decay producing bacteria which negatives the chemical treatment.

Referring to the accompanying drawings which are made a part hereof and on which similar reference characters indicate similar parts,

Figure 1 is an elevation of a pole formed of spirally wound members and illustrating the application of my invention.

Figure 2, a fragmentary detail perspective of the top portion of the pole viewed from below,

Figure 3, a fragmentary front elevation showing my device applied to a wooden pole and cross arm,

Figure 4, a side elevation of the structure of Fig. 3,

Figure 5, a top plan view of the structure shown in Fig. 3,

Fig. 6, a fragmentary top plan view of a slightly modified form of clamp applied to a wooden pole and cross arm,

Figure 7, a fragmentary side elevation showing my invention applied to a metallic tubular pole and metal cross arm,

Figure 8, a section on the line 6—6 of Fig. 3, and

Figure 9, a fragmentary top plan view of a further modified form of clamp applied to a wooden pole and cross arm.

In the accompanying drawings a pole or post 10 is shown constructed of a series of oppositely wound members or strands L- shaped in cross section and welded together at their crossing points. A cross arm 11 of ordinary wooden construction is secured to the pole 10 by my improved clamp which fits about the pole and embraces the cross arm at opposite sides of the same.

In lieu of the metal pole 10, a wooden pole may be used as I have illustrated in Figs. 3 to 6, or if preferred a pole of some other material, as for example concrete or the like, may be employed.

In Figs. 1 to 5 I have shown a clamp which comprises a pair of spaced curved pole engaging portions 12 which conform to the shape of the pole upon which the device is used each of such curved portions 12 being of a length sufficient to extend slightly less than half the distance around the pole and having end portions 13 extending outwardly parallel to the diameter of the pole and provided with bolts 14 engaging opposed cooperating curved members 15 for binding the curved members tightly around the pole. The curved portions 12 and 15 are preferably provided with protuberances or bosses 16 and 17 respectively punched in by means of a center punch or the like, such protuberances being adapted to engage the surface of the pole for preventing rotation of the clamp on the pole. In order to strengthen the bolt engaging ends of the curved member 14, reinforcing strips 18 are preferably welded thereto at each side of the same.

Each pole is provided with two clamps having the curved portions 12, one upper and one lower, and these curved portions are connected at their extremities by means of 5 yoke portions 19 which extend around and embrace the cross arm 11 for holding the same firmly in position. The portions 12 and 19 preferably are formed of an endless strap as shown or if desired they may be 10 formed of separate parts.

In the structure just described yokes 19 are disposed transversely substantially at right angles to the cross arm, however, in order to secure a better bracing connection 15 yoke members 19' of slightly greater length may be provided as shown in Fig. 6, but with the construction of the clamp otherwise the same. Such members 19' extend from the pole to the cross arm at an acute angle. 20 Also bolts 20 may be employed to prevent endwise movement of the cross arm in the yokes or brackets which hold it.

In Fig. 7 I have shown a hollow metal pole 21 and a metal cross arm 22 with which 25 clamps similar to those shown in Figs. 1 to 6 may be used with the use of a short bolt 23 in lieu of the bolts 20 for holding the cross arm in place.

In Fig. 9 I have shown a wooden pole 10 30 and a cross arm 11 which are fastened together by means of brackets or straps 25 having integral curved portions 26 which extend around the pole, the brackets and connecting curved portion forming a substantially U-shaped yoke with the extremities of the brackets engaging the cross arm 11 and being held in position by means of 35 bolts 27. The points of connection between the brackets and the integral curved members 26 are offset at 28 and are perforated to receive bolts 29 which secure an opposed curved clamping member 30 in a relation so that the portions 30 and 26 when drawn together by the bolts 27 cooperate to clamp a 40 pole or post therebetween.

It will be readily apparent that I have 45 provided clamping means for securing a cross arm to a pole which is of very simple and inexpensive construction, which does not weaken the pole or cross arm or expose it to decay producing bacteria.

It will be obvious to those skilled in the art that various changes may be made in my device without departing from the spirit of 50 the invention, and I, therefore, do not limit myself to what is shown in the drawings and described in the specification but only as set forth in the appended claims.

Having thus fully described my said invention, what I claim as new and desire to 55 secure by Letters Patent, is:

1. The combination with an upright pole and a transverse cross arm, of means for attaching the cross arm upon the pole comprising a pair of opposed clamping members,

and means for drawing the clamping members toward each other about a pole independently of the engagement with the cross arm, one of said clamping members having its ends extended and formed to embrace the 70 cross arm, substantially as set forth.

2. The combination with a pair of cross members, of means for securing the cross members together comprising two pairs of opposed clamping members arranged on one 75 of the cross members in relation spaced in accordance with the thickness of the other cross member, and means for drawing said clamping members together for tight engagement about one of the cross members 80 independently of the engagement with the cross arm, the spaced clamping members on the same side of one cross member having its ends extended and formed to embrace the other cross member, substantially as set 85 forth.

3. A clamp for securing a member transversely of a post comprising an endless band 90 formed of spaced yokes disposed in similar relation and adapted to embrace the transverse member with the sides of the respective yokes connected by post engaging portions, additional post engaging portions disposed in opposition to said last mentioned post engaging portions, and means for binding 95 the posts engaging portions together, substantially as set forth.

4. A clamp comprising a pair of similarly arranged spaced body engaging members having their corresponding ends connected 100 by a transversely extending integrally formed strap, and additional body engaging members arranged in opposed relation and secured to said first mentioned body engaging members, substantially as set forth. 105

5. A clamp for securing a member transversely of a post, comprising a band forming spaced yokes disposed in similar relation and adapted to embrace the transverse member with corresponding sides of the yokes 110 connected by a post engaging portion, an additional post engaging portion disposed in opposition to said last mentioned post engaging portion, and means for binding the post engaging portions together, substantially as set forth. 115

6. A clamp comprising a pair of similarly arranged, spaced body engaging members, having their corresponding ends connected by a transversely extending integrally 120 formed strap, additional body engaging members arranged in opposed relation and secured to said first mentioned body engaging members by bolts adapted to clamp the body engaging members about the body, substantially as set forth.

7. A cross arm clamp comprising a pair of similarly arranged post engaging members having their corresponding ends laterally offset and connected by transversely ex- 125 130

tending straps adapted to engage a cross arm, additional post engaging members also having their corresponding ends laterally offset and arranged in opposed relation to the first mentioned post engaging members, the offset ends of the said opposed post engaging members being provided with openings adapted to receive bolts for clamping

the said members about the post, substantially as set forth.

10

In witness whereof, I have hereunto set my hand at Habana, Cuba this 21st day of February, A. D. nineteen hundred and twenty-eight.

ADOLPH W. MALONE.
